JESSE E. MATEER, OF WILKINSBURG, PENNSYLVANIA, ASSIGNOR TO WESTINGHOUSE ELECTRIC AND MANUFACTURING COMPANY, A CORPORATION OF PENNSYLVANIA.

HIGH-VOLTAGE TRANSFORMER.

1,129,499.

Specification of Letters Patent.

Patented Feb. 23, 1915.

Application filed January 10, 1912. Serial No. 670,528.

To all whom it may concern:

Be it known that I, JESSE E. MATEER, a citizen of the United States, and a resident of Wilkinsburg, in the county of Allegheny and State of Pennsylvania, have invented a new and useful Improvement in High-Voltage Transformers, of which the following is a specification.

My invention relates to high-voltage electrical apparatus and it has special reference to series or current-type transformers which are adapted to supply energy at low voltages to the trip coils of circuit interrupters and electrical measuring instruments.

The object of my invention is to provide a transformer of the class above indicated that shall be considerably less expensive than those heretofore constructed for similar service conditions.

According to my present invention, I utilize a single insulating sleeve or bushing through which the high-potential conductor, constituting one winding of the transformer, is threaded and on which the low-voltage winding and the core member are mounted, and I separate the low-voltage apparatus from the remainder of the high-voltage winding by means of an insulating spacing structure which is similar to a high-potential line insulator.

Figure 1 of the accompanying drawings is a partially sectional elevation of a transformer constructed in accordance with my invention, Fig. 2 is a plan view of a section of the transformer shown in Fig. 1, and Fig. 3 is a detail view, on a larger scale, of one end of the insulating sleeve or bushing of the other figures.

Referring to the drawings, the transformer here shown comprises an insulating sleeve or bushing 1 which may be of any suitable structure capable of sustaining very high voltages, annular core members 2 and 3 which surround the bushing 1 and are centrally located thereon, low-voltage coils 4 and 5 which are wound upon the core members 2 and 3, respectively, a supporting frame 6 and a spacing insulator 7. The supporting frame 6 consists of a metal box or casing comprising an upper section 8 and a lower section 9 which are secured together by bolts 10, a pedestal 11 and a base 12. A metal tube or rod 13 extends upwardly from the upper half 8 of the frame 6 and serves 55 as a pin on which the insulating spacing

structure 7, which is similar in form to a high-voltage line insulator, is mounted. The insulator 7 comprises a series of insulating bells or caps 14 set one over another and secured together by cement.

A high-potential winding 15, comprising several turns of insulated conductor, is produced by threading the conductor back and forth through the sleeve or bushing and allowing a sufficient external loop to pass over the insulating support 7. After the high-potential winding is threaded into place, the several turns of which it is composed are taped together and it is clamped to a metal cap 16 with which the insulator 7 is provided, as shown in Fig. 1. In order to economize space, I prefer to utilize a sleeve or bushing of the condenser type comprising a plurality of cylinders 17 and 18 of alternately insulating and conducting materials. The inner cylinder of the bushing is made of insulating material, and the smallest conducting cylinder, which surrounds the inner insulating cylinder, is electrically connected to one turn of the high-potential winding 15 by means of a conducting member 19. The high-potential winding is provided with terminals 20 and 21.

The structure of my invention has the advantage of requiring only a single high-potential sleeve or bushing instead of two, as has heretofore been considered necessary when a multi-turn high-potential winding is utilized. For very high voltages this saving is particularly noticeable, since the cost of the high-potential bushings is a large item in the cost of the device. The casing 9 is separated from the outer conducting cylinder of the insulating bushing 1 by some suitable means, such as collar 22, of insulating material, in order to prevent the casing from constituting a part of a short-circuited turn of the transformer.

I desire that variations which do not depart from the spirit of my invention shall be included within its scope.

I claim as my invention:

1. A high-potential transformer comprising an insulating sleeve, a supporting structure therefor, an annular core member surrounding the sleeve within the supporting structure, a low-potential coil on the coil member, a high-potential winding comprising a plurality of turns threaded through the sleeve, a rod projecting from the sup- 110

- porting member substantially at right angles to the insulating sleeve, and a high-potential insulator mounted on the rod for supporting the high-potential winding.
5. Electrical apparatus comprising an insulating sleeve, a core member surrounding the sleeve, a winding threaded through the sleeve, a supporting casing for the sleeve having a projection extending outwardly substantially at right angles to the sleeve and an insulator mounted on the projection and spacing the winding from the core exteriorly of the sleeve.
10. Electrical apparatus comprising an insulating sleeve, a supporting member embracing the sleeve, a winding threaded through the sleeve, and means mounted upon said supporting member for supporting the said winding exteriorly to the sleeve.
15. Electrical apparatus comprising an insulating sleeve, a supporting member embracing the sleeve, a winding threaded through the sleeve, and an insulator mounted on said supporting member and supporting the said winding exteriorly to the sleeve.
20. Electrical apparatus comprising an insulating sleeve, a supporting member embracing the sleeve, a winding threaded through the sleeve, and an insulator mounted on said supporting member and supporting the said winding exteriorly to the sleeve.
25. Electrical apparatus comprising an insulating sleeve, a magnetizable core sur-
- rounding the sleeve, a low-tension winding surrounding the core, a conducting casing surrounding the core and low-tension winding and supporting the insulating sleeve, a high-tension winding comprising a plurality of turns threaded through the insulating sleeve, and means mounted upon the conducting casing for supporting the said high-tension winding exteriorly to the sleeve.
30. Electrical apparatus comprising an insulating sleeve, a magnetizable core surrounding the sleeve, a low-tension winding surrounding the core, a conducting casing surrounding the core and low-tension winding and supporting the insulating sleeve, and insulated means carried by the said casing for supporting the high-potential winding exteriorly to the sleeve.
35. Electrical apparatus comprising an insulating sleeve, a magnetizable core surrounding the sleeve, a low-tension winding surrounding the core, a conducting casing surrounding the core and low-tension winding and supporting the insulating sleeve, and insulated means carried by the said casing for supporting the high-potential winding exteriorly to the sleeve.
40. Electrical apparatus comprising an insulating sleeve, a magnetizable core surrounding the sleeve, a low-tension winding surrounding the core, a conducting casing surrounding the core and low-tension winding and supporting the insulating sleeve, and insulated means carried by the said casing for supporting the high-potential winding exteriorly to the sleeve.
45. Electrical apparatus comprising an insulating sleeve, a magnetizable core surrounding the sleeve, a low-tension winding surrounding the core, a conducting casing surrounding the core and low-tension winding and supporting the insulating sleeve, and insulated means carried by the said casing for supporting the high-potential winding exteriorly to the sleeve.

In testimony whereof, I have hereunto subscribed my name this 28th day of Dec. 1911.

JESSE E. MATEER.
